UNITED STATES PATENT OFFICE.

ROBERT A. JEWETT, OF WORCESTER, MASSACHUSETTS.

ELECTRIC GAS-LIGHTING DEVICE.

971,010.

Specification of Letters Patent. Patented Sept. 20, 1910.

Application filed July 3, 1907. Serial No. 381,982.

To all whom it may concern:

Be it known that I, ROBERT A. JEWETT, a citizen of the United States of America and a resident of Worcester, in the county of 5 Worcester and State of Massachusetts, have invented certain new and useful Improvements in Electric Gas-Lighting Devices, of which the following is a specification.

This invention relates to an igniting device 10 for gas burners and is particularly adapted for lighting incandescent gas lamps although the invention may be used equally as well with other types of burners.

It has for its object the production of a 15 device which may be operated by the turning of the valve which controls the main gas supply and which is adapted in its movement to ignite the gas passing from said burner.

It has for a further object the production 20 of a device adapted to emit a limited amount of gas through a by-pass by the operation of the main valve and ignite the gas thus emitted to provide a suitable jet to light the 25 gas passing from said burner.

The invention consists in certain novel 30 features of construction and arrangement of parts which will be readily understood by reference to the description of the drawings and to the claims hereinafter given.

Of the drawings: Figure 1 represents a section through an incandescent gas burner showing the invention applied thereto. Fig. 2 represents a section of the valve of said 35 burner drawn to an enlarged scale. Fig. 3 represents a section through said valve and casing, the cutting plane being on line 3—3 on Fig. 2 showing the by-pass in said valve in position to admit gas thereto. Fig. 4 represents a section on line 4—4 showing the valve in the same position as in Fig. 3. Fig. 5 represents a similar section to Fig. 3 showing the valve in closed position. Fig. 6 represents a similar section to Fig. 4. 45 Fig. 7 represents the valve in closed position. Fig. 8 represents a similar section to Fig. 6 showing the valve in open position. Fig. 9 represents a similar section to Figs. 3 and 5 showing the valve in the same position as in Fig. 7, and Fig. 9 represents an elevation of 50 the wipers for creating an electric spark for the purpose of lighting the gas.

Similar characters designate like parts throughout the several figures of the drawings.

In the drawings, 10 represents an ordi-

nary burner supplied with an incandescent mantle 11 of any well-known construction and surrounded by the usual glass globe 12 which is provided in its walls with a plurality of openings 13 for the admission of air to the interior of the globe.

The burner casing 10 is provided with a valve 14, the passage 15 through which communicates with the passage 16 when in open 60 position and controls the flow of gas through said passage by a movement of the valve 14 about its axis. The outer end of the passage 16 communicates with the pipe 17 leading to the main gas supply. In addition to 70 the main passage 16 the casing 10 is also provided at its outer end with a small inlet 18 which communicates with a radial hole 19 extending to the center of the valve 14 and communicating with the interior of the 75 tubular member 20 secured to the valve 14 in axial line therewith.

The upper end of the tube 20 is bent over as indicated at 21 so that the mouth thereof is at one of the openings 13 in the globe 12 80 and points directly at the mantle 11. The extreme outer end of the tube 20 is provided with a suitable wiper 22 which co-acts with a companion wiper 23 secured by means of a clip 24 to the globe 12 in such a manner 85 that said wiper will extend across the opening 13. An electric wire 25 leads from said wiper 23 around the burner casing 10 to a suitable battery 26 from which a return wire 90 communicates with the burner casing to complete an electric circuit. This circuit is normally broken when the valve 14 is closed, the wipers 22 and 23 being separated in this position. When, however, the valve or cock 14 is turned to permit gas to flow through 95 the burner 10 the wiper 22 will be moved about the axis of the valve 14 and wipe across the pendent wiper 23 and complete the circuit and then immediately break the same, this action causing a spark to be generated, which is adapted to ignite any gas 100 which may be emitted at this time through the tube 20.

As will be seen by Figs. 5 and 6, when the stop 27 is against the shoulder 28 in the casing 10 the passage 15 through the valve will be out of line with the passages 16 in the casing thus preventing the flow of gas to the burner while at the same time the radial hole 19 is also out of alignment with the 110 small passage 18 extending through said casing thus preventing the flow of any gas.

- to and through the tube 20. As soon, however, as the thumb-piece 29 is moved about the axis of said valve 14 in the direction of the arrow on Figs. 3 to 6 inclusive, the radial 5 opening or hole 19 in the valve will be brought into alinement with the passage 18 thus permitting the gas from the pipe 17 to pass to and through the tube 20 and out of the mouth thereof at its bent end 21.
- 10 Only a limited amount of gas is passed into and through the tube 20 as the continuation of the movement of the valve 14 in the direction of the arrows on Figs. 3 to 6 inclusive causes the radial opening 19 to pass 15 by the passage 18 and thus shut off the flow of gas through the tube. This movement, however, of the valve 14 in the direction of the arrow causes the wipers 22 and 23 to operate to cause a spark which will be timed 20 to occur when the tube 20 has been filled with gas, this spark lighting the gas in said tube and causing a flame to be emitted from the mouth thereof extending to the mantle 11 which at this time is being supplied with 25 gas through the main passage 16, the valve 14 having been turned sufficiently to cause the passages 15 and 16 to have become alined thus permitting the flow of gas from the main supply to the burner. The advantage 30 of a device of this kind which will simultaneously cause the gas from the main supply to pass through and from the burner and ignite said gas thus emitted from the burner is obvious.
- 35 This makes a very simple construction of a lighting device particularly adapted for incandescent gas lamps which is very effective in its operation while the number of parts necessary to secure the desired result 40 is reduced to a minimum.
- It is believed that the many advantages and operation of this device will be fully apparent without further description.
- Having thus described my invention, I 45 claim:
1. The combination of a gas burner provided with a passage to the main gas supply; a valve located at one side of and parallel to said burner adapted to control the flow of gas through said passage and having two radial holes in its casing between the valve plug and the main gas supply; a by-pass communicating with one of said holes through said valve adapted to permit the passage of a limited supply of gas therethrough during the movement of said valve; a tubular extension outside the limits of said burner communicating with said by-pass and terminating in a radial portion adapted 55 to emit the gas in the direction of said burner; an ignition device at the mouth thereof; and means for operating said ignition device by the movement of said valve.
  2. The combination of a gas burner pro-

vided with a passage to the main gas supply; 65 a valve located at one side of and parallel to said burner adapted to control the flow of gas through said passage and provided with means for admitting a portion of the gas supply to the center of said valve; a tube secured to said valve in axial line therewith communicating with said passage; a clip secured to the globe of said burner provided with a wiper finger; a wire secured to said clip adapted to conduct 70 an electric current to said wiper finger; and a co-acting wiper finger secured to said tube.

3. The combination of a gas burner provided with a passage to the main gas supply; 80 a valve located at one side of and parallel to said burner adapted to control the flow of gas through said passage; a wiper finger secured to the globe of said burner; an axial extension to said valve revoluble therewith; and a wiper finger secured thereto adapted when the valve is operated to turn on the gas to coat with the burner wiper finger to ignite the gas passing from 85 said burner.

4. The combination of a gas burner provided with a horizontal passage to the main gas supply; a valve located with its axis transverse to said passage and adapted to control the flow of gas through said passage; a globe to said burner provided with a plurality of air inlets; a wiper finger secured to said globe at one of said inlets; a tubular member secured to said valve and revoluble therewith; means for admitting a limited supply of gas to said tubular member during the rotation of said valve; and a wiper finger at the outlet to said tubular member adapted during the rotation of said valve to coat with the wiper finger affixed to the globe to cause an ignition of the gas 100 passing from said tubular member.

5. The combination of a gas burner provided with a passage to the main gas supply; a valve located at one side of and parallel to said burner adapted to control the flow of gas through said passage and provided with means for admitting a portion of the gas supply to the center of said valve; a tube secured to said valve in axial line therewith communicating with said passage; a clip detachably secured to a fixed member outside the limits of the burner and provided with a wiper finger; a wire secured to said clip adapted to conduct an electric current to said wiper finger; and a co-acting wiper finger secured to said tube.

Signed by me at Boston, Mass., this 29th day of June, 1907.

ROBERT A. JEWETT.
